UNITED STATES PATENT OFFICE

ALLEN NOHR, OF MILWAUKEE, WISCONSIN, ASSIGNOR OF ONE-HALF TO JOSEPH P. ELLIS, OF MILWAUKEE, WISCONSIN

STERILIZER

Application filed March 20, 1931. Serial No. 523,979.

The invention relates to sterilizers and has for an object the provision of a simple and inexpensive flame-heated dry-heat sterilizer which is particularly adapted for the sterilization of brushes, such as tooth-brushes.

The invention further consists in the several features hereinafter set forth and more particularly defined by the annexed claims.

In the accompanying drawing

Fig. 1 is a perspective view of a brush sterilizer embodying the invention;

Fig. 2 is a side view of the sterilizer with a tooth-brush mounted therein, parts of the sterilizer being broken away and parts being shown in section;

Fig. 3 is a top plan view of the sterilizer, and

Fig. 4 is a transverse sectional view of a modified form of sterilizer.

In the drawing, the numeral 10 designates a flat handle-forming frame, which may be constructed of sheet metal. At one end of the frame is secured a heat-conducting sheath 11 of U-shaped cross-section forming therein a sterilizing chamber receiving the bristle portion of a brush 12, in the present instance indicated to be a tooth-brush. The outer end of the sheath 11 is preferably, though not necessarily, closed, as seen in Fig. 2. The edge portions of the sheath are provided with lips 13 which pass through slots 14 formed in the frame 10 and are bent inwardly on the outer face of the frame, as seen in Fig. 3, to anchor the sheath in place.

In the modified form of sterilizer shown in Fig. 4, the sheath 11' is provided at its edges with outturned lips 13' which are clamped between the frame 10' and inturned flanges 14' formed along the edge portions of the frame.

The sheath 11 is preferably formed of wire screen of suitable mesh, although in some instances it may be formed of thin sheet metal or other material of good heat conductivity.

When the tooth-brush 12 is to be sterilized it is placed in the sterilizing sheath 11, in which it fits fairly closely. The sheath 11 is then subjected from below to a flame 15 from any suitable source, the screen of the sheath serving to distribute the heat of the

flame about the bristles without danger of scorching the bristles or other parts of the brush, since the flame does not pass through the screen. The flame may be produced in any one of various ways convenient to the user and need be applied for only a few seconds.

What I claim as new and desire to secure by Letters Patent is:

1. A dry-heat sterilizer comprising a supporting member having slots therein, and a flame-heated U-shaped heat-conducting sheath having edge portions secured in said slots, said sheath being adapted to receive therein an object to be sterilized and preventing the direct access of flame to the object.

2. A dry heat sterilizer comprising a metal screen casing adapted to be heated by a flame impinging thereon and adapted to receive therein an article to be sterilized, said screen casing permitting the flow therethrough of hot sterilizing gases but preventing the direct access of the flame to the article.

3. A dry heat sterilizer comprising a sheet metal supporting member forming a handle at one end, a metal screen sheath adapted to be heated by a flame impinging thereon and having edge portions secured to the other end of said supporting member to form therewith a compartment adapted to receive an article to be sterilized, said sheath permitting the flow therethrough of hot sterilizing gases but preventing the direct access of the flame to the article.

4. A dry heat sterilizer comprising an air-permeable metal screen casing adapted to receive therein an article to be sterilized and adapted to be exteriorly heated by an adjacent incandescent heat source to a non-scorching sterilizing temperature.

In testimony whereof I affix my signature.

ALLEN NOHR.
